Fig.19

Fig.20

FIG. 1 is a perspective view taken from the left front side of a door embodying my new design;

FIG. 2 is a rear elevation of the door shown in FIG. 1;

FIG. 3 is an enlarged right side elevation of the door shown in FIG. 1, foreshortened in several places;

FIG. 4 is a top view of the door shown in FIG. 2;

FIG. 5 is a section taken as indicated by the lines and arrows 5-5 in FIG. 2;

FIG. 6 is a section taken as indicated by the lines and arrows 6-6 in FIG. 2;

FIG. 7 is a section taken as indicated by the lines and arrows 7-7 in FIG. 3;

FIG. 8 is a perspective view taken from the left front side of another door embodying my new design;

FIG. 9 is a rear elevation of the door shown in FIG. 8;

FIG. 10 is a right side elevation of the door shown in FIG. 8;

FIG. 11 is a top view of the door shown in FIG. 9;

FIG. 12 is a section taken as indicated by the lines and arrows 12-12 in FIG. 9;

FIG. 13 is a perspective view taken from the left front side of another door embodying my new design;

FIG. 14 is a rear elevation of the door shown in FIG. 13;

FIG. 15 is a right side elevation of the door shown in FIG. 13;

FIG. 16 is a top view of the door shown in FIG. 14;

FIG. 17 is a section taken as indicated by the lines and arrows 17-17 in FIG. 14;

FIG. 18 is a perspective view taken from the left front side of another door embodying my new design;

FIG. 19 is a perspective view taken from the left front side of another door embodying my new design; and

FIG. 20 is a perspective view taken from the left front side of another door embodying my new design.

Portions have been foreshortened on the drawings for convenience of illustration.

The shading employed does not connote actual appearance but is an expedient to best illustrate the various embodiments.

This application is a division of U.S. patent application Ser. No. D. 23,254, filed June 1, 1970, and discloses and claims, in part, the subject matter disclosed and claimed therein as well as the applications cross-referenced therein.

I claim:

The ornamental design for a door, as shown and described.
